Patented Aug. 24, 1920.

INVENTOR
John Palahniuk.
BY *Dredick Myers*
his ATTORNEY

UNITED STATES PATENT OFFICE.

JOHN PALAHNIUK, OF BRULE MINES, ALBERTA, CANADA.

CORK-EXTRACTOR.

1,350,383.

Specification of Letters Patent. Patented Aug. 24, 1920.

Application filed March 14, 1919, Serial No. 282,661. Renewed June 2, 1920. Serial No. 386,048.

To all whom it may concern:

Be it known that I, JOHN PALAHNIUK, a citizen of Austria, residing at Brule Mines, Prov. of Alberta, and Dom. of Canada, have 5 invented certain new and useful Improvements in Cork-Extractors, of which the following is a specification.

This invention relates to improvements in devices for removing bottle corks, and has 10 as its special object the provision of an implement by means of which a cork may be readily extracted from within a bottle neck in an easy and convenient manner.

This object is attained by the novel construction and combination of parts herein- 15 after described and shown in the accompanying drawing, forming a material part of this disclosure, and in which:—

Figure 1 is a side elevational view showing a cork extractor made in accordance 20 with the invention.

Fig. 2 is another side elevational view of the same, taken from another plane, and

Fig. 3 is a side elevational view, similar 25 to Fig. 1, and showing a modified form of construction.

In carrying out the invention, use is made 30 of a straight cylindrical handle 10 preferably of wood and having rigidly engaged upon opposite sides, by screw bolts or rivets 11, a pair of arms 12, their lower ends 14, which extend to some distance below the handle, being resilient so that they can be entered into various sizes of bottle necks.

35 Formed upon the inner sides of the resilient elements 14 are a plurality of sharp, upwardly turned spurs 15, adapted to engage in the cork which is to be extracted, and in order to guide the resilient arms 14, with 40 respect to the opening in the bottle, other spring arms 18 are secured by rivets or like fastenings 19, to the handle through the arms 12, the spring arms 18 having flat elliptical ends 20, curved so as to slide freely 45 over the neck of a bottle as indicated more particularly in Fig. 1.

Formed axially through the handle 10 is an opening 22 containing a rod 23, having at its lower end a convex disk-like head 24, 50 adapted to make contact with the upper surface of the cork, so that the same may

be pressed firmly against the spurs 15 by pressure applied to the concavo-convex cap 25, suited to engage at the upper end of the handle 10 when in a depressed position. 55

In the modification shown in Fig. 3, the resilient arms 14 are formed with slots 28 into which extend the arms 30 formed with the slideable bar 23, the arms taking the place of the convex head 24 as shown in Figs. 60 1 and 2, and, due to the angularity of the arms 30, when they are caused to engage with the upper surface of the slots 28, the arms are caused to spring slightly inward, forcing the spurs 15 into the cork. 65

The foregoing description, taken into connection with the drawings, is believed to form a complete disclosure of the invention.

Having thus described my invention what I claim as new and desire to secure by Letters Patent, is.

1. In a cork extractor, the combination with a cylindrical handle, of a pair of resilient arms engaged therewith, said arms extending below and adapted to enter a 75 bottle neck, a plurality of upturned spurs formed integrally with said resilient arms, means for guiding said arms as they are forced into the bottle, a rod slideable centrally in said handle and a convex head formed at the lower end of said rod adapted to contact with the upper end of the cork whereby it may be forced upon said spurs. 80

2. In a cork extractor, the combination with a straight cylindrical handle, of a pair 85 of resilient arms engaged upon opposite sides of said handle and extending therebelow, a plurality of upturned sharply pointed spurs formed integrally with said resilient arms, guides affixed upon said handle adapted to guide said arms as they are entered into a bottle, a rod slidably engaged within said handle, means at the upper end of said rod whereby it may be manipulated, and a pair of angular arms at 90 the lower end of said rod, said angular arms being adapted to enter into slots formed in said resilient arms whereby they are brought toward each other as the cork is extracted. 95

In testimony whereof I have affixed my 100 signature.

JOHN PALAHNIUK.
